The essential features of the design reside in the portions shown in full lines. The portions of a motor scooter shown in broken lines at the front and rear are included for illustrative purposes only.

I claim:

The ornamental design for a motor scooter cab or the like, substantially as shown and described.
